STENCILING DEVICE

Selvar G. Johnson, Chicago, Ill.

Application December 23, 1931, Serial No. 582,706

13 Claims. (Cl. 101—125)

My invention relates to stenciling, and includes among its objects and advantages a hand stencil stamp embodying certain features which I have found particularly advantageous in such devices.

5 In the accompanying drawing:

Figure 1 is an end elevation of a device according to the invention;

Figure 2 is a side elevation partly in section;

Figure 3 is a top plan view partly in section;

10 Figure 4 is an enlarged sectional view taken along the line 4—4 of Figure 3; and

Figure 5 is a plan view of a backing sheet associated with the stencil sheet.

In the embodiment of the invention selected for 15 illustration, 10 designates a hollow body provided with a handle 12 mounted upon a strap 14 having its ends fastened to the body 10 by rivets 16. The top of the body is closed by means of a cover comprising portions 18 and 20 recessed at 22 for 20 receiving the strap 14. The cover protects the fingers of the user from becoming soiled by the stenciling ink in the body 10. Each cover portion is provided with a depending flange 24 slightly narrower than the portions themselves to permit 25 the flanges to be positioned within the body 10 and in abutment with the vertical side walls 26 of the body, as indicated in Figure 3 where the upper ends of the flanges 24 abut the side wall portion 31, and the lower ends abut the side wall portion 33. When the cover is closed, the flanges 24 abut each other as illustrated in Figure 1. At 30 this time the cover portions 18 and 20 are firmly associated with the body 10, since the strap 14 prevents lateral or endwise movement of the portions. The flanges 24, in addition to preventing lateral movement of the inner ends of the cover portions 18 and 20, function as pivots for the cover portions when their outer ends are lifted upwardly as indicated in dotted lines in Figure 2.

35 The length of the flanges is such that the walls 26 will be spread apart slightly when the flanges are pressed therebetween. Thus the flanges will be effectively held in frictional assembly with the body 10 by the pressure of the sides 26 upon the 40 ends of the flanges. I have provided a grip member 28 upon each of the cover portions.

The body 10 has a framework of vertical peripheral walls, indicated as a whole by the reference character 26. The entire framework comprises the inner peripheral frame 30 and the outer peripheral frame 32. The frame 32 is larger than the frame 30 and the narrow peripheral groove between them receives and holds the upturned edges of the metallic bottom 36.

45 55 Each frame 30 and 32 is made up of two dupli-

cate U-shaped elements. The element 31 of frame 30 begins at the lower right hand corner of Figure 3 and extends across the end and along the other side to the upper left hand corner. The element 33 completes the inner frame 30, extending from the upper left hand corner of Figure 3 across the left end and along the lower side to the lower right hand corner. It will be seen that rotation of element 31 one hundred eighty degrees about the center of Figure 3 will bring it 10 within the position of element 33.

The frame 32 is made up in the same way of elements 35 and 37 except that the diagonally opposite abutment joints are at the corners of the frame remote from the joints of the frame 30, 15 as clearly shown in the upper right hand corner of Figure 3.

Each of the elements 31, 33, 35, and 37 comprises a short leg and a long leg and a crosspiece or bight connecting the legs into a U-shaped structure. The bights of the elements 31 and 37 together make up the right end of the completed frame, as viewed in Figure 3, and the bights of elements 33 and 35 similarly make up the left end of the frame. All four bights have arcuate lower 25 edges indicated at 38 in Figures 1 and 4, conforming to the curvature of the bottom 36.

Along the sides of the bottom 36 the edges are turned up as at 34 in Figure 4, and entered between the frames 30 and 32. Along the ends the 30 edge is slotted before turning up into tongues 39 to reduce the die work needed to shape the metal. These fingers enter between the lower edges of the inner end walls 40 constituting the bights of the frame elements 31 and 33, and the outer end walls 35 42 constituting the bights of the frame elements 35 and 37. After the bottom is assembled with the frame work, the whole may be spotwelded together.

An inking pad or stencil backing 46 is placed 40 adjacent the curved foraminous bottom 36. The sides of the inking pad are clamped to the sides 26 of the body 10 by means of metal straps 48. Screws 50 having annular grooves 52 in their heads clamp one of the straps to the body, while 45 the other strap is clamped thereto by ordinary screws 54. The screws 50 serve an additional function as attaching means for one end of a stencil sheet 56. One edge of the stencil sheet is glued to a paper backing sheet 58 as indicated 50 at 59.

In Figure 5, I have shown the glued together portions of the stencil sheet and the backing sheet as being provided with a plurality of openings 60. These openings are spaced apart dis- 55

tances equal to the spacing of the screws 50, so that one edge of the stencil may be easily and quickly associated with the body 10 by merely passing the screws 50 through the openings 60.

5. The grooves 52 receive the edges of the material defining the openings 60, so that this edge of the stencil sheet is effectively connected with the screws when it is stretched across the inking pad 46.

10. The backing sheet 58 may be temporarily associated with the stencil sheet or permanently associated therewith depending upon the nature of the work being done. In Figure 5, I have indicated a line of perforations 62 in the backing sheet 58 which permits the sheet to be detached from the remaining portion glued to the stencil sheet 56. The opposite edge of the backing remains free, while the opposite edge of the stencil is fastened to the opposite wall 26 by means of a tension bar 64. This bar is provided with two wide portions 66 having slots 68 for receiving screws 70. Nuts 72 upon the screw 70 are arranged for clamping the tension bar against its side 26 of the bottom 10.

25. Referring to Figures 2 and 4, it will be noted that the lower edge of the bar 64 is bent around a small wire 74 for providing a lateral projection arranged to press against the edge of the stencil sheet 56 and clamp the latter against the inking pad 46. The inner ends of the screws 70 are fixedly connected with the wall 26, so that the screws will remain fixed even though the nuts 72 are loosened for releasing the tension bar 64.

30. It will be noted that the tension bar 64 is associated with the screws 70 by a sliding movement in contact with the stencil sheet 56 in a direction tending to stretch the sheet. With the sheet 56 as taut as it can conveniently be held by hand, the bar is placed in a slightly lower position than that shown in Figure 4, and then slid up to the position of Figure 4. This movement of the bar is guided by engagement of the screws 70 in slots 68. As soon as the movement is completed, a tightening of the nuts 72 clamps the whole in assembled position ready for use.

35. I have shown longitudinal lines 76 and 78 and transverse lines 80 and 82 printed upon that face of the backing sheet 58 adjacent the stencil sheet 56. These lines indicate the top, bottom, and side limits within which reading matter should be cut in the stencil. I have also shown longitudinal lines 84 and 86 representing areas within which printing matter should be confined when stenciling postcards. These lines, in addition to defining the limits of the stencil sheet 56, also serve as marks to guide the user in positioning sheets to be stenciled.

40. The foraminous bottom is constructed from material having sufficient rigidity to resist distortion when the device is placed under stenciling pressure, while the inking pad 38 is of sufficient thickness and flexibility to provide compensation for irregularities of surface met with in stenciling. I provide an outer facing 88 of fine linen cloth adjacent the outer face of the inking pad which prevents any of the fibers of the inking pad from being worked into the stencil sheet 56.

45. Without further elaboration the foregoing will so fully explain my invention that others may, by applying current knowledge, readily adapt the same for use under various conditions of service.

I claim:

50. 1. In a device of the type described, a hollow body having an open top, a handle supporting strap having its ends fastened to the ends of the

body, and a cover for closing said open top, said cover comprising a pair of sections, each section having a flange arranged to abut the other flange and the side walls of the body, each section having a recess in its outer end for receiving said strap. 5

2. In a device of the type described, a hollow body having an open top, and a cover for closing said open top, said cover comprising two portions, each portion having a flange arranged to abut the other flange and provide pivotal guidance when the cover is positioned upon the body. 10

3. In a device of the type described, a hollow body having sides and an open top, a cover for closing said open top, said cover comprising two 15 portions having flanges arranged to abut each other and said sides, to provide pivotal guidance for said cover portions.

4. The combination with a stencil hand stamp body having an inking pad associated therewith, of a stencil sheet having one end connected with one side of the body, projections carried by the opposite side of the body, a tension bar having slots for receiving said projections, said tension bar being arranged for fastening the opposite 20 edge of said stencil sheet in taut condition across said inking pad, said tension bar being arranged for connection with said projections by a sliding movement in a direction tending to place said stencil sheet under tension, and means associated 25 with said projections for firmly clamping the tension bar to its respective side of the body.

5. In a stencil hand stamp comprising a body having an ink feeding bottom, a stencil sheet having one edge detachably connected with one side 30 of said body and stretched across said bottom, a tension bar for clamping the opposite edge of said stencil sheet to the body, means for detachably connecting the tension bar with said body, means guiding said tension bar into assembled position 40 by a sliding movement tending to stretch said stencil sheet, and a bead comprising a part of said tension bar for firmly clamping the stencil sheet to said body.

6. A stencil hand stamp comprising a hollow 45 body having a foraminous bottom, an inking pad stretched across said foraminous bottom and having its edges clamped to the sides of said body, the clamping means comprising metal straps and screws passing through the straps and threaded 50 into the sides of said body, a stencil sheet having openings for receiving the screws associated with one of said metal straps, a tension bar for fastening the opposite edge of the stencil sheet to the opposite side of the body, said tension bar 55 having a bead for clamping the stencil sheet firmly against the inking pad, and screw means for applying pressure to said tension bar.

7. In a device of the type described, a hollow body having an opening and a cover for closing 60 said opening, said cover comprising two parts, each part having a flange arranged to frictionally engage portions of said body for holding the cover in assembled relation therewith, said flanges providing pivotal guidance for said parts. 65

8. In a device of the class described, two U-shaped frame members with the ends of their legs abutting to define a complete peripheral enclosure, two more U-shaped frame members defining a larger enclosure with a space between, a 70 curved bottom having its edges positioned between said frame members, and fastening means uniting all said frame members and the bottom into a rigid unit, the bights of said frame members hav- 75

ing convex lower edges conforming to the curvature of said bottom member.

9. In a device of the class described, two U-shaped frame members with the ends of their legs abutting to define a complete peripheral enclosure, two more U-shaped frame members defining a larger enclosure, a curved bottom having its edges positioned between said frame members, and fastening means uniting all said frame members and the bottom into a rigid unit, the joints where the ends of the legs abut being mismatched, the bights of said frame members having lower edges conforming to the curvature of said bottom member.

10. In a device of the class described, two U-shaped frame members with the ends of their legs abutting to define a complete peripheral enclosure, two more U-shaped frame members defining a larger enclosure, a downwardly bellied 20 foraminated bottom having its edges entered between said frame members, the bights of said frame members having arcuate convex lower edges abutting said bottom member.

11. In a device of the type described, a pair of 25 frame members defining a peripheral enclosure,

each frame member comprising a pair of U-shaped elements, each U-shaped element having legs of unequal length, the ends of one element in each frame abutting the ends of the other element in that frame, and a bottom having its edges secured between said frame members. 5

12. In a device of the type described, a pair of frame members defining a multisided enclosure, each frame member comprising a pair of U-shaped elements, each U-shaped element having legs of unequal length, the ends of one element in each frame abutting the ends of the other element in that frame, and the joints between the abutting ends upon one side of the frame being mismatched with respect to the joints between the 15 abutting ends upon the opposite side.

13. A stamp body comprising a peripheral framework made up of an inner and an outer frame, each frame made up of two duplicate portions arranged with their ends abutting, each 20 portion extending across one end of the frame, along a minor fraction of one side of the frame, and along a major fraction of the other side of the frame.

SELVAR G. JOHNSON. 25
